UNITED STATES PATENT OFFICE.

THOMAS FLINTOFF, OF CLAREMONT, WESTERN AUSTRALIA, AUSTRALIA.

ARTIFICIAL TOOTH.

No. 828,617.

Specification of Letters Patent.

Patented July 21, 1908.

Application filed February 2, 1907. Serial No. 355,432.

To all whom it may concern:

Be it known that I, THOMAS FLINTOFF, a citizen of the Commonwealth of Australia, residing at Claremont, Western Australia, 5 Australia, and whose post-office address is corner of High and William streets, Fremantle, Western Australia, have invented certain new and useful Improvements in Artificial Teeth; and I do hereby declare the 10 following to be a full, clear, and exact description of the invention, such as will enable others skilled in the art to which it appertains to make and use the same, reference being had to the accompanying drawings, and to 15 letters or figures of reference marked thereon, which form a part of this specification.

The invention relates to improvements in artificial teeth of that type in which the crown is mounted on a metal key having 20 tangs adapted to be embedded in the mouth plate.

The object of the invention is to provide a key that will present a large anchorage surface for the crown; one that will be light and 25 strong and to provide means to cause frictional engagement between the key and crown to permit vertical adjustment of the latter before permanently securing the parts together by the vulcanite.

30 The invention consists in certain novel features of construction and arrangement of parts as will now be described and illustrated in the accompanying drawing in which—

Figure 1 is a view showing a tooth constructed in accordance with the invention and as attached to a mouth plate. Fig. 2 is a vertical section of the tooth and keypiece, and Fig. 3 is a horizontal section on line x—x of Fig. 2.

40 In the drawing a designates a tooth having or being formed with a dovetail recess or key bed a' of any approved section. This recess is formed in the body part of the tooth but does not extend the full length of the same.

45 Into the recess is inserted a metal key-piece or anchor b which conforms to the contour of the recess and is preferably made hollow, as shown, to reduce the weight. Said key-piece is formed with two normally parallel 50 tangs b' adapted to be inserted into the soft vulcanite or other backing on the plate b²

when a set of teeth is being built up. The tangs are subsequently bent, as shown in dotted lines Fig. 3, and embedded in the vulcanite serving to hold the teeth rigidly in 55 place. These key-pieces b are further formed on each side with a transverse pin as c which rest flush into corresponding recesses or grooves c' formed in the teeth on each side of the recess a', said recesses c' being about 60 twice as wide as the pin arms, as shown in dotted lines, Fig. 1, so as to permit of the tooth being built on the carrying member b² to be vertically adjustable so as to coincide with the bite of the wearer. By bending the 65 pins c back from the position shown in Fig. 3, until they come into contact with the rear wall of the recesses, the slanting sides of the key piece will be brought into contact with the sides of the dovetail key-bed a' and hold 70 the key piece b by friction in the adjusted position. When the key piece is embedded in the carrying member b² the soft vulcanite will then fill up the spaces in the grooves c' above and below the pins. 75

By means of these improvements I obtain a cheap and strong construction for connecting artificial teeth to their carrying member, thus obviating the expense of platinum inset pins and their costly mode of insertion. It 80 will be seen that the keys with their recesses or key beds form a rigid anchorage for the teeth to their carrying member and further by such means a large anchorage area for the teeth is obtained and so distributing the 85 breaking strain on the tooth, as with the present inset pins, the strain is restricted and therefore intensified onto one part of the tooth. 90

I claim:

1. An artificial tooth having a recess formed therein and a key mounted in said recess having pliable tangs formed thereon and lateral pins taking into laterally formed recesses in said tooth. 95

2. An artificial tooth having a central recess formed therein and a smaller lateral recess on each side of the latter communicating therewith, and a key having its body portion mounted in the central recess and lateral pins 100 adjustably mounted in the lateral recesses.

3. An artificial tooth having a central re-

cess formed therein and a smaller lateral recess on each side of the latter communicating therewith, a hollow metal key conforming to the contour of the central recess having lateral pins projecting into and adapted to slide in the lateral recesses, and a pliable tang formed on each side of the key.

In testimony that I claim the foregoing as my invention, I have signed my name in presence of two subscribing witnesses.

THOMAS FLINTOFF.
